Patented Jan. 14, 1919.

UNITED STATES PATENT OFFICE.

FRANK CHADIMA, OF CEDAR RAPIDS, IOWA.

BRAKE.

1,291,402.

Specification of Letters Patent. Patented Jan. 14, 1919.

Application filed July 10, 1916. Serial No. 108,507.

To all whom it may concern:

Be it known that I, FRANK CHADIMA, a citizen of the United States, residing at Cedar Rapids, in the county of Linn and State of Iowa, have invented certain new and useful Improvements in Brakes; and I do hereby declare the following to be a full, clear, and exact description of the invention, such as will enable others skilled in the art 10 to which it appertains to make and use the same.

This invention relates to brakes of the band compression type, and the object of the invention is to produce an improved 15 brake adapted by its construction to insure quick and uniform expansion of the band, when released, entirely clearing the drum, and correspondingly quick and uniform contact of the band with the drum, in the act of 20 setting the brake, the action being to draw the ends of the band toward each other and vary close to the drum and thereby avoiding practically all side strain on the drum shaft and bearing.

25 The brake as herein illustrated is shown as applied to the driving mechanism of a creamery churn, but is applicable to other purposes as well.

In the accompanying drawing, forming 30 a part of this specification, Figure 1 is a side elevation of a brake embodying my invention. Fig. 2 is an end elevation to the left of the section line 1—1. Fig. 3 is an elevation similar to Fig. 1, showing the 35 brake parts detached.

In the drawing the numeral 5 denotes a part of the main frame of a creamery churn, the frame having a cross-bar 6 to which the 40 brake apparatus is mainly attached. In suitable bearings 7 is mounted a rock-shaft provided with a hand-lever 8. The rock-shaft also carries shifter arms 9 coöoperating with a sleeve 10 to actuate a clutch, not shown.

To the driving shaft 11 is attached the 45 brake-drum 12. Nearly surrounding the drum is an annular ring 13, provided with set-screws 14 at intervals, which may be set to accurately limit the expansion of the

brake-band 15, shown in Fig. 2 in close contact with the drum. By this means, when 50 the brake - band is expanded it is forced against the set-screws which hold it slightly and uniformly spaced away from the drum. The ring connects at its lower ends with a bracket 16 attached to the cross-bar 6. Between forked standards 6^a are pivoted short bell-crank levers 17 connecting at 18 with the looped ends of the brake-band. The lever arms 19 engage with the heads of links 20, whose lower ends are pivoted to a lever 21, 55 pivoted at 22. The long arm of this lever connects at 23 with a rod 24 hinged at 25 to a short arm 26 of the hand lever 8.

It will be seen that the raising of the hand-lever will operate to disengage the 60 clutch and will set the brake. In the operation of churning, especially, it is desirable that the brake act smoothly, firmly and with precision. This is effected in a very satisfactory manner by the device above described, 65 the band being drawn in from both ends and very close to the periphery of the drum, so that nearly the entire circumference thereof is brought at once into frictional contact with the brake-band, to which any desired 70 tension may be applied by the operator through the hand-lever.

Having thus described my invention, I claim:

The combination of a rock-shaft having 80 clutch - shifting arms attached thereto, a hand-lever secured to said shaft, a brake-lever carried by said shaft, a pulling rod linked thereto, a lever to which said rod is connected at its other end, a supporting 85 bracket and pivot for said last-named lever, a pair of links connecting with its shorter arm, a pair of connecting bell-crank levers, and a brake - band connecting by its ends 90 with said bell-crank levers.

In testimony whereof I affix my signature in presence of two witnesses.

FRANK CHADIMA.
